Filed Apr. 30, 1965, Ser. No. 85,050

Term of patent 14 years

(Cl. D29—19)

(Granted under Title 35, U.S. Code (1952), sec. 266)

FIG. 1

FIG. 3

FIG. 2

FIG. 1 is a front elevational view of a medal or similar article, showing my new design;

FIG. 2 is a side elevational view as seen from the left of FIG. 1; and

FIG. 3 is a rear elevational view thereof, the appearance of same being similar to the rear view of the medal disclosed in FIG. 2 of my Design Patent No. 185,862 patented August 11, 1959.

It is understood that my design may be embodied in such articles as a badge, medal, medallion, plaque, or sign, without departing from the spirit of my invention.

The essential features of my design are shown in full lines.

The invention described herein, if patented, may be manufactured and used by or for the Government for

governmental purposes, without the payment to me of any royalty thereon.

I claim:

The ornamental design for a medal or similar article, as shown and described.
